UNITED STATES PATENT OFFICE.

EMILIO ZERTUCHE, OF PUEBLA, MEXICO.

INSULATOR.

SPECIFICATION forming part of Letters Patent No. 650,445, dated May 29, 1900.

Application filed October 28, 1899. Serial No. 735,082. (No model.)

To all whom it may concern:

Be it known that I, EMILIO ZERTUCHE, of Puebla, Mexico, have invented a new and Improved Insulator, of which the following is a full, clear, and exact description.

My invention relates to an insulator or support for electric wires, and has for its object to provide a simple, cheap, strong, and efficient device of the above-indicated class.

10 The invention will be fully described hereinafter and the features of novelty pointed out in the appended claims.

Reference is to be had to the accompanying drawings, forming a part of this specification, 15 in which similar characters of reference indicate corresponding parts in all the views.

Figure 1 is a perspective view of my improved insulator. Fig. 2 is a sectional plan on line 2 2 of Fig. 3, and Fig. 3 is a sectional 20 elevation on line 3 3 of Fig. 2 and showing the insulator attached to a support.

The insulator consists of any suitable material, such as glass or porcelain, and is made substantially in the shape of a rectangular 25 prism the side edges of which have been rounded off.

In two of its side surfaces, about half-way between the top and the bottom, the insulator is provided with horizontal grooves A, 30 starting from opposite ends, and these grooves communicate with a vertical slot A', extending diagonally, as shown best in Fig. 2, and reaching from the top surface to the level of the bottom of the grooves A. The insulator 35 at the meeting-points of the slot A' with the grooves A is formed with overhanging projections A², and the corners below these projections in the planes of the grooves A are rounded, as shown at A³. In a plane at a 40 right angle to that formed by the Z-shaped passage A A' the other two sides of the insulator are provided with curved grooves A⁴, which also extend partly over the top and bottom surfaces of the insulator. These grooves 45 are adapted to receive a wire E, which is wound around the insulator and around a supporting-arm D to secure the insulator thereon, as shown in Fig. 3.

To strengthen the insulator, an S-shaped 50 piece of metal B may be embedded in its bottom surface.

The line-wire C enters through one of the grooves A, passes under the corresponding tongue A², then diagonally across the slot A' to an engagement with the round edge A³, under 55 the other tongue A², and finally out through the other groove A. It will be seen that the wire is securely held in position, that it is not bent sharply and therefore is not liable to break, that the stretching of the wire may be effected after the wire has been placed in the insulator, and that the stretching may readily be performed in a very efficient manner.

Having thus described my invention, I claim as new and desire to secure by Letters 65 Patent—

1. An insulator consisting of a body having a Z-shaped passage the end members of which extend in opposite side surfaces of the insulator while the central or diagonal member extends through to one of the end surfaces of the insulator.

2. An insulator consisting of a body having substantially-parallel grooves in opposite side surfaces, and a diagonal slot connecting 75 opposite ends of said grooves and extending through to one end surface of the insulator.

3. An insulator consisting of a body having a Z-shaped passage the end members of which extend in opposite side surfaces of the 80 insulator while the central or diagonal member extends through to one of the end surfaces of the insulator, the insulator being provided with overhanging tongues at the junction of the diagonal member with the end 85 member of the passage.

4. An insulator consisting of a body having a Z-shaped passage the end members of which extend in opposite side surfaces of the insulator while the central or diagonal member extends through to one of the end surfaces of the insulator, the insulator being provided with overhanging tongues at the junction of the diagonal member with the end 90 member of the passage, and with rounded 95 edges below said tongues.

5. An insulator consisting of a body having a Z-shaped passage the end members of which extend in opposite side surfaces of the insulator while the central or diagonal member extends through to one of the end surfaces of the insulator, and a groove adapted 100

to receive a fastening-wire and extending in a plane at a right angle to that of the Z-shaped passage.

6. An insulator consisting of a body having four side faces and two end faces, and provided with a Z-shaped passage the end members of which extend in opposite side surfaces of the insulator, while the central or diagonal member extends through to one of the end surfaces of the insulator, and transverse grooves extending in the other side surfaces of the insulator, in a plane at a right angle to that of the Z-shaped passage.

7. An insulator consisting of a body having a Z-shaped passage the end members of which extend in opposite side surfaces of the insulator while the central or diagonal member extends through to one of the end surfaces of the insulator, and a reinforcing-strip embedded in the opposite end surface of the insulator.
